UNITED STATES PATENT OFFICE.

EDWARD HEYDON, OF INDIANAPOLIS, INDIANA; EMMA HEYDON, EXECUTRIX OF EDWARD HEYDON, DECEASED, ASSIGNOR TO EMMA HEYDON, OF INDIANAPOLIS, INDIANA.

POLE-REENFORCING SLEEVE.

Application filed March 5, 1923. Serial No. 622,862.

It is the object of my invention to provide any of the parts had rusted. Further, it has resulted in breaking of the sleeve-halves in the heavy pounding to which they were sometimes subjected in putting them together or taking them apart, when such a long relative movement was required. Moreover, such sleeves were of the same size at both ends, in order that the tongues and grooves would co-operate throughout the sleeve length, and so were not adapted for use at pole joints.

Both wooden poles and steel poles tend to become weak and to break at certain points. In the wooden pole, this is usually on the line just at or above the ground. In the steel pole, it is on the same line, just at or above the ground; and also at every joint in the pole or just above it, where the lower end of a smaller tubular pole section is inserted into the upper end of the next lower but slightly larger tubular pole section.

To save poles which are weakened so that they are in danger of breaking, or which perhaps have already broken, pole sleeves have been used to surround the pole and project lengthwise on both sides of the weakened part or break. The most effective of these have been made in two parts, each of which extended halfway around the pole, the two longitudinal edges of each part being provided respectively with a radially outwardly projecting tongue and a radially inwardly opening groove; so that the two halves of the sleeve could be applied to the pole at longitudinally spaced points thereon, with the tongue and groove of one part in line with the groove and tongue respectively of the other part, and the two sleeve-halves then brought together by sliding one part relatively to the other to cause the tongues and grooves to interfit. To take such a sleeve off, if that is required for any reason, the operation is reversed.

This has formed a very effective pole-sleeve construction, and has saved many poles which would otherwise have been total losses. However, it has involved some difficulties, because the two sleeve-halves had to be slid longitudinally with respect to each other for the full length of the sleeve, either to put the sleeve together or take it apart. This long sliding movement was sometimes very difficult to obtain because of various obstructions which might be encountered in the construction of the sleeve itself or in the pole or its surroundings, especially when

By my present invention, I make it possible to put the two sleeve-parts together and take them apart much more easily, and with a much shorter longitudinal movement between the sleeve-parts, and to apply the sleeve effectively to pole joints as well as elsewhere. In doing this, I make noncontinuous both the tongues and the groove-containing ribs with which the tongues co-operate, instead of making them continuous as heretofore, with gaps or spaces at one or more points in their length at least equal in span to the length of the parts of the cooperating ribs or tongues; so that in putting the sleeve parts together it is necessary to displace them relatively to each other only by the half of the distance between centers of adjacent parts of a tongue, instead of by the whole length of the sleeve, and to move them relatively only by that distance in order to lock the two parts together or unlock them.

The accompanying drawing illustrates my invention: Fig. 1 is a vertical sectional view through a multi-section tubular steel pole equipped at various points with pole-reenforcing sleeves of my invention, the two lower sleeves being shown as filled with grout, while the uppermost sleeve is shown as snugly fitting the pole without grout; Fig. 2 is an enlarged perspective view of the lowermost sleeve shown in Fig. 1, with the two sleeve-parts interlocked; Fig. 3 is a section on the lines 3-3 of Figs. 1 and 2, but before the grout has been put in place; Fig. 4 is an enlarged elevation of the uppermost sleeve of Fig. 1, with the two sleeve-parts displaced sufficiently to unlock them; and Fig. 5 is a plan of the sleeve shown in Fig. 4.

The pole shown is a multi-section steel pole, having a lower part 10 set in the ground 11 but projecting upward therefrom,

an intermediate part 12 the lower end of which projects some distance into the upper end of the section 10, and an upper section 13, the lower end of which projects into the upper end of the section 12. This pole has several well-defined points where it is most apt to corrode and become weakened by natural conditions, due to the retaining of moisture in contact with the metal. These are 10 at the ground line 11 for the section 10, and at the upper ends of the sections 10 and 12 for the sections 12 and 13 respectively. Therefore, it is at these points that the pole is most apt to need reenforcing sleeves, 15 which may be put around the pole at these points, as indicated in Fig. 1.

The reenforcing sleeve may fit the pole fairly snugly, with no material intervening space, as the uppermost sleeve 14 as shown in Fig. 1, or may be slightly spaced from the pole by internal lugs 15 on the sleeve, as is shown for the intermediate and lower sleeves 16 and 17 in Fig. 1, in which latter cases the intervening space between the sleeve and 20 the pole may be filled with grout 18. The lowermost sleeve 17 is of the same size at both top and bottom, because it is not intended to extend past a pole-joint; but the two sleeves 14 and 16 are of smaller diameter 25 at the top than at the bottom, because they co-operate with the pole at joints, and at each joint the pole is smaller above the joint than it is below the joint. This two-diameter feature is made possible by my invention. The 30 one-diameter sleeve is shown in Figs. 2 and 3, and the two-diameter sleeve in Figs. 4 and 5; but either can be used, as conditions require. As so far described, except for the two-diameter feature, the structure is old, 35 and my invention is applicable to any of the types of sleeves shown, whether one-diameter or two-diameter sleeves, and whether with or without the internal lugs 15.

Each sleeve 14, 16, or 17 is made of a plurality of parts 21 and 22. Preferably these parts are halves, so that two are used to form a complete sleeve, each part extending for 180° around the pole circumference. Each sleeve-part at one longitudinal edge has a 40 discontinuous tongue formed by a plurality of spaced tongue-sections 23, equally spaced apart. Preferably there is a tongue-section at each end, so that there is one more tongue-section than space. On the other longitudinal edge, each sleeve-part has a plurality of spaced rib-sections 24, which on their radially inner surfaces are provided with radial inwardly facing grooves 25 of the proper size and shape to fit the tongue-sections 23. The rib-sections correspond in 45 number to the tongue-sections, and are correspondingly spaced. Any space between adjacent tongue-sections or rib-sections is preferably longer than a tongue-section or rib-section itself. This is the preferred arrange- 50

ment; but in any case, the space between adjacent rib-sections is as long as or slightly longer than a tongue-section, and vice versa. The tongue-sections in a sleeve-part are preferably all co-planar; so are the groove-sections. 55

By this construction, it is possible to assemble the sleeve, whether on a pole or not, by displacing the two sleeve-parts longitudinally merely by the distance from the center of a space to the center of the adjacent tongue-section or rib-section. In other words, with the tongue-sections and rib-sections similarly spaced, and with a section rather than a space at each end, the longitudinal displacement between the two sleeve-parts necessary to assemble or disassemble the sleeve is the invert of twice the number of tongue sections or rib-sections, minus 1—that is, if there are four tongue-sections, the necessary displacement is only one-seventh of the sleeve length, as shown in Fig. 4, while if there are three tongue-sections, the necessary displacement is only one-fifth of the sleeve-length, as shown in Fig. 2. By making this displacement, the two sleeve-parts can be put together so that the tongue-sections of each sleeve-part are in alinement with the grooves in the rib-sections of the other sleeve-part, whereupon the two sleeve-parts may be moved relatively longitudinally to each other to lock the two sleeve-parts together. This makes the longitudinal driving of a sleeve-part necessary to lock or unlock them only a fraction of what was formerly required, so that the breakage is greatly reduced, and the liability of encountering obstructions in the movement is correspondingly reduced. 60

When the sleeve is assembled over a joint, as are the sleeves 14 and 16 of Fig. 1, one sleeve-part is put on the pole at the joint, and the other sleeve-part is put on at the necessary distance above the joint so that the rib-sections and tongue-sections of it will interdigitate with those of the other; and then the higher sleeve-section is driven downward to lock the rib-sections and tongue-sections, and seat both sleeve-parts on the upper end of the adjacent lower pole-section. The 65 change in diameters where there is a two-diameter sleeve, as for a joint, is at a space between sections of the tongue and ribs, as is indicated in Fig. 4. If there is no joint where the sleeve is applied, the location of the sleeve-parts may be somewhat more flexible, but in general the same procedure is followed. When the two sleeve-parts are locked together, the grout 18, if it is used, may be poured in place. 70

I claim as my invention:—

1. A pole-reenforcing sleeve, comprising a plurality of parts which together form the complete sleeve, one edge of each sleeve-part having a series of spaced tongue-sections 75

tions and the other a series of spaced groove-sections so that the tongue-sections of one part may be received in the groove-sections of the other part to lock the parts of the sleeve together, the spaces between tongue-sections being sufficiently long to receive the groove sections and those between groove-sections being sufficiently long to receive the tongue-sections.

10 2. The combination set forth in claim 1, with the addition that the sleeve at its opposite ends is of different diameters and has an intermediate diameter-offsetting portion.

15 3. A pole-reinforcing sleeve, comprising a plurality of parts which together form a complete sleeve, said parts at their meeting longitudinal edges being provided with interfitting locking members for locking the parts together, and the sleeve being of a

20 different diameter at one end from what it is at the other.

4. A pole-reinforcing sleeve, comprising a plurality of parts which together form a complete sleeve, said parts at their meeting longitudinal edges being provided with interfitting locking members for locking the parts together, the interfitting locking parts at one set of meeting edges between sleeve-parts being formed by a plurality of spaced 25 tongue-sections on one sleeve-part and a plurality of spaced groove-sections on the other sleeve-part.

30 5. The combination set forth in claim 4, with the addition that the tongue-sections are all co-planar and the groove-sections are all co-planar, and the spaces between each set of sections are sufficiently long to receive the sections of the other set.

35 6. The combination set forth in claim 4, with the addition that the two ends of the sleeve are of different diameters, and the sleeve has an intermediate diameter-offsetting portion joining the two portions of different diameters.

7. The combination set forth in claim 4, 45 with the addition that the tongue-sections are all co-planar and the groove-sections are all co-planar, the spaces between each set of sections are sufficiently long to receive the sections of the other set, the two ends of the 50 sleeve are of different diameters, and the sleeve has an intermediate diameter-offsetting portion joining the two portions of different diameters.

8. A pole-reinforcing sleeve, comprising a 55 plurality of parts which together form a complete sleeve, said parts at their meeting longitudinal edges being provided with interfitting locking members which are interengaged and disengaged by relative longitudinal movement between the sleeve-parts, and the sleeve being of a different diameter 60 at one end from what it is at the other.

9. A pole-reinforcing sleeve, comprising a 65 plurality of parts which together form a complete sleeve, said parts at their meeting longitudinal edges being provided with interfitting locking members which are interengaged and disengaged by relative longitudinal movement between the sleeve-parts 70 of materially less than the length of the sleeve.

10. A pole-reinforcing sleeve, comprising a plurality of parts which together form a complete sleeve, said parts at their meeting 75 longitudinal edges being provided with interfitting locking members which are interengaged and disengaged by relative longitudinal movement between the sleeve-parts of materially less than the length of the 80 sleeve, and the sleeve being of a different diameter at one end from what it is at the other.

In witness whereof, I have hereunto set my hand at Indianapolis, Indiana, this 1st 85 day of March, A. D. one thousand nine hundred and twenty-three.

EDWARD HEYDON.
